UNITED STATES PATENT OFFICE.

JOSEPH BAHL AND JOSEPH CHRISTIAN BAHL, OF CHICAGO, ILLINOIS.

MUSIC-LEAF TURNER.

No. 811,993.

Specification of Letters Patent.

Patented Feb. 6, 1906.

Application filed March 24, 1905. Serial No. 251,889.

To all whom it may concern:

Be it known that we, JOSEPH BAHL and JOSEPH CHRISTIAN BAHL, citizens of the United States, and residents of Chicago, in the county of Cook and State of Illinois, have invented an Improvement in Pianos and Organs—a Music-Leaf Turner—of which the following, taken in connection with the accompanying drawings, is a specification.

10 Our invention is an apparatus for automatically turning the leaves of music. The music-leaf-turning mechanism being mounted on the front board of pianos and organs, the leaves of music are turned over by means of 15 spring-actuated flat metal arms, all of which are secured to circular cups pivoted on a single axle, said arms being successively released by means of an escapement which is operated by means of a finger-lever or a pneumatic releasing device, whichever is the most convenient to the player, the escapement being provided with both releasing means, and is carried out as follows, reference being had to the accompanying drawings, wherein—

25 Figure 1 is a front view of the music-leaf-turning mechanism. Fig. 2 is a top view of the same. Fig. 3 is a side view of a clasp. Fig. 4 is a side view of a hinged tooth in normal position. Fig. 5 is a side view of a hinge-30 tooth bent to the rear. Fig. 6 is a front view of a finger-lever. Fig. 7 is a side view of the same. Fig. 8 is a rear view of the ratchet-wheel of the escapement and part of the levers with their pawls. Fig. 9 is a front perspective view of the vise. Fig. 10 is a front perspective view of a circular cup containing 35 a spring. Fig. 11 is a three-quarter view of the bellows and pedal. Fig. 12 is a three-quarter view of an equivalent escapement, 40 the first tooth being in normal position. Fig. 13 is the same, the first tooth being bent to the rear. Fig. 14 is a three-quarter view of an equivalent escapement. Fig. 15 is a three-quarter view of an equivalent escapement. 45 Fig. 16 is a front view of the arms when they are on the left side of the front board, showing the arrangement by which the arms disappear behind same. Fig. 17 is a top view of the same. Fig. 18 is a part of the front board 50 of a piano or a piano-case organ, showing the arrangement of the various parts of the music-leaf turner with the exception of the bellows mounted thereon. Fig. 19 is the same, but showing a different disappearing arrangement. Fig. 20 is a front perspective view of

the rack portion of an organ, showing, with the exception of the bellows, the arrangement of the various parts of the music-leaf turner mounted thereon. Fig. 21 is the front board of a piano or a piano-case organ, showing the 60 arrangement of the various parts of the music-leaf turner, with the exception of the bellows, mounted in a sunken panel. Said front board is only partly shown.

Similar letters and numerals refer to similar parts wherever they occur in the different parts of the drawings.

The complete music-leaf turner consists of the music-leaf-turning mechanism A, the vise B, the finger-lever C, the bellows D, and the 70 flexible tube E.

As the preferred form, the music-leaf-turning mechanism A is mounted on the rear face of the front boards of pianos and organs, the leaf-turning arms 1 projecting in front of the 75 front face of said front boards by passing through a slit thereon. Said music-leaf-turning mechanism consists of a plurality of flat metal music-leaf-turning arms 1, the outer ends of which terminate in spring-pressed 80 clasps 2. Their inner ends are secured to circular cups 3, each arm being secured to a cup. Said cups 3 are all perforated in the center, through which passes the axle 4. All the cups are pivoted on this axle 4. Inside 85 of said cups are the coiled springs 5, which throw the arms 1 a half-revolution from the right to the left, one spring being in each cup. One end of said springs is fastened to the vertical groove 64 on the axle 4 and the other 90 end is fastened to the inner walls of their respective cups. To provide a means of strengthening and weakening the tension of the springs 5 within the cups 3, the axle 4 has fastened to it a ratchet-wheel 21, and a pawl 95 22, engaging the teeth of said ratchet-wheel, is pivoted on the base-plate 23 of the case 15. Said pawl is yieldingly held against the teeth of said ratchet-wheel by the spring 24. To increase the tension of said springs 5, the axle 100 4 is turned to the right. The arms 1 being held in check by the escapement 11 prevent the cups 3 from revolving, to whose inner walls one end of said springs is fastened, while the axle 4, to which the other ends are fastened, 105 winds up said springs. To weaken the tension of said springs, the pawl 22 is disengaged from the said ratchet-wheel 21. This causes the axle 4 to revolve to the left, thus unwinding the said springs. The leaves of music 110

are secured to the leaf-turning arms 1 by means of the clasps 2, consisting of two jaws 6 and 7. The jaw 6 is a continuation of the arm. The jaw 7 is pivotally secured to the 5 jaw 6 by the pin 8. Said pin supports the spring 9, which presses the two jaws together at their lower ends. The jaw 7 is provided with a loop 10 at its upper end, which extends a little higher than the jaw 6. When 10 the jaw 6 of the first arm and the jaw 7 of the last arm are pressed together by the player, the jaws 7 of all the clasps come in contact at their looped ends 10 and cause all the clasps to simultaneously open. In this way the 15 leaves of music are simultaneously released from the clasps 2 when through with them. The inner surfaces of the jaws 6 and 7 are roughened by cross-lines. This prevents the leaves of music slipping out. The arms 1 20 are held on the right side of the front board of piano or organ against the tension of their springs 5 by the escapement 11. Said escapement successively releases said arms and consists of a shaft 12, pivoted at 13 and 14 on 25 the walls of the casing 15. Said shaft has mounted thereon a plurality of hinge-constructed teeth 16, said teeth projecting from said shaft in different directions and are situated in back of each other, so arranged that 30 when the shaft 12 is partially revolved to the right the first tooth is removed from in front of the first arm, thus releasing same. Said partial revolving movement causes the tooth immediately behind the first tooth to come 35 in front of the second arm, thus holding in check all the rest of the arms. Another partial revolution in the same direction removes the second tooth from in front of the second arm, releasing same, and the tooth immedi- 40 ately behind the second tooth comes in front of the third arm, these partial revolutions being continued until the last tooth releases the last arm. The movement which removes the last tooth from in front of the last 45 arm does not replace it by another tooth. Another partial revolution completes one revolution of the escapement and causes the first tooth to again project in the path of said arms 1. Said teeth 16 are all of hinge con- 50 struction, consisting of two parts 17 and 18, which are pivotally connected by the pin 19. A spring 20, one end of which is secured to the part 17 and the other end to the part 18, normally holds said part 17 extended. When 55 the pressure occasioned by returning all or one or two of the arms, as the case may be, is brought to bear on any one of the teeth 16 which happen to project in the path of said arms, the part 17 yields to the rear, tension- 60 ing the springs 20. In this way the arms are brought within the escapement without the teeth 16 interfering. The part 17 yielding to the rear allows all arms to pass within the escapement. After the arms have passed 65 the part 17 resumes its normal position, and

thus prevents the arms turning to the left until released, as described above.

The successive partial revolving of the escapement 11, and thereby successively releasing the arms 1, is brought about by means of the finger-lever C or the pneumatic releasing device consisting of the bellows D, the flexible tube E, the metal tube 25, and the metal cap therefor 26, which fits over the tube 25. The finger-lever C is situated on the lower 75 part of the front board of pianos and organs and is pivoted on a pin 28, the rear end 29 having connection with the rod 30. The front end 31 is the part upon which the player presses to release an arm. A spring 80 32 is tensioned whenever the part 31 is depressed and causes said part to regain its normal position. When the pressure thereon is released, the rod 30 connects the finger-lever C to the lever 33, which is pivotally secured to 85 the shaft 12 on the one end and the other end makes the connection with the rod 30 by means of the slit 34. The player pressing on the part 31 of the finger-lever C the part 29 is raised. This motion being imparted to the 90 rod 30 causes an upward motion of the lever 33. Said lever 33 has pivoted thereon a pawl 37, which engages a ratchet-wheel 38, secured to the shaft 12 of the escapement 11. A spring 39 yieldingly holds the pawl 37 95 against the teeth of said ratchet-wheel. Said upward motion of the lever 33 causes the pawl 37 to partially revolve the escapement. When the pressure on the finger-lever C is released, the lever 33 falls back in normal position by reason of the spring 40. The pawl 37 then falls back on the following tooth of the ratchet-wheel 38. This partial revolution of the escapement 11 releases one arm in the manner above described. The part 31 of the 100 finger-lever C is pivotally secured to the part 29 by the pin 35, and when said finger-lever is not used it is folded upward into a recess the shape of the part 31. The player's hands being both occupied, the leaf-turning arms 1 are 105 released by means of the pneumatic releasing device D E 25 26. A stud 41 on the metal cap 26 travels in the slot 34^a. Said cap 26 fits over a metal tube 25, and when air is forced in the metal tube 25 from without the cap 26 110 is lifted and causes an upward movement of the lever 33^a. Said lever is provided with a pawl 37^a, a spring 39^a for said pawl, and a spring 40^a. These parts operate in the same way as the parts of the lever 33. When an 115 arm is released by means of the finger-lever C, the pneumatic releasing device D E 25 26 remains inactive and the pawl 37^a serves to prevent the escapement from turning back in the wrong direction. When the pneumatic 120 releasing device is used, the pawl 37 then serves this purpose, the lever 33 remaining inactive. The air-pressure is provided by means of a bellows D, operated by a pedal 42, which is situated at the lower part of the pi- 125 130

ano or organ next to the soft, loud, and other pedals now in use. The flexible tube E connects the bellows D with the metal tube 25. It being flexible, allows the free movement of 5 the front board. The bellows D consists of an upper and a lower plate, 43 the upper and 44 the lower. Said plates are pivotally connected by the pin 45, which also serves to secure the bellows to the inner side of the piano 10 or organ case. A leather portion 46, arranged in folds, is fastened to said plates 43 and 44, so that the space between them is air-tight, with the exception of the two inlets 47 on the plate 43 and the flexible tube E. Said inlets 15 are provided with flaps 48 on their inner sides, which open inward, caused by suction. When the plate 44 after having been raised by the player's foot depressing the pedal 42 again resumes its normal position, the opening of 20 said flaps allows air to pass within the bellows to replenish the exhausted supply of air, the plate 44 again resumes its normal position by reason of the spring 49, which is tensioned. Whenever the pedal 42 is depressed, 25 the air-pressure within the bellows caused by the upward movement of the plate 44 closes the flaps 48, so that the air is forced up through the flexible tube E, connected to the bellows. It is obvious that the construction 30 and proportion of said bellows can be varied and that the inlets 48 can also be placed on the plate 44.

The vise B is mounted on a support 50, which is pivotally secured in an opening of the 35 front board, so that when the music-leaf turner is not in use said support 50 is reversed—the face upon which the vise is mounted is turned to the rear of the front board, and the rear face comes to the front. A latch 27 locks 40 said support 50, so that when in use it remains parallel to the surface of the front board. Said vise B consists of two jaws 51 and 51^a, which are separated and closed by means of a thumb-screw 52, on one half of whose shaft 45 the threading is turned opposite to the threading on the other half. This arrangement causes the jaws 51 and 51^a to separate when the thumb-screw 52 is turned in one direction and to close when turned in the opposite direction. The thumb-screw 52 is pivoted on 50 the bearings 53. This vise serves to hold the leaves of music together, as in a bound book, keeps them in the center of the front board, and keeps the leaves of music within reach of 55 the clasps 2. The jaw 51 is provided with an indentation 54 and the jaw 51^a with a projection 55, which fits into the indentation 54. The inner surfaces of said jaws are also roughened by cross-lines. The said indentation, projection, and cross-lines cause the 60 leaves of music to be more firmly held.

The arms 1 have each pivotally secured to them a small plate 56, which serves to mark the arms that are to be re-turned whenever 65 a piece of music has a passage which is

to be repeated. This plate 56 when not in use is in parallel position to the arms 1, and when a piece of music is to be repeated the arm upon which it is secured is marked, so as to be easily distinguishable from the rest of 70 the arms, by turning the plate 56 secured thereto in vertical position, so that it projects above the arm. To prevent the arms 1 from clashing together, they are provided with rubber collars or buffers 57. These coming 75 in contact with each other keep the arms 1 apart. When not in use, the arms 1 are allowed to entirely disappear from the front face of the front board by removing a slide 58 from in front of an opening 62, which is large 80 enough to admit the clasps 2. The arms 1 are held close to the rear face of the front board by the projection 59 on the inner end of the sliding bar 60. Said sliding bar passes through the front board and ends in a handle 85 61. To cause the arms 1 to project in front of the front board, the sliding bar 60 is pulled out, bringing the said arms with it, as the dotted lines show. The slide 58 is then moved over the opening 62, and thus prevents 90 the said arms returning to the inside. A flap 65 covers up the long slit 62 when the music-leaf turner is not in use and is secured by hinges to the front board above said slit. The said flap is swung upward when it is de- 95 sired to use the music-leaf turner.

An equivalent escapement, Figs. 12 and 13, consists of a shaft 66, having two teeth 67 and 68 situated on the front end thereof. The tooth 67 is situated a short distance to 100 the rear of the tooth 68, said teeth projecting from said shaft, so that in normal position the tooth 68 projects in the path of the leaf-turning arms and the tooth 67 projects just outside of the path of said arms, so that when the shaft 66 is partially revolved the tooth 68 is removed from the path of the first arm, thus releasing same. The tooth 67 with the same movement comes in front of 105 the second arm before the first arm is released, thus holding all the following arms in check. As the shaft 66 again revolves back to its normal position, the tooth 67 is removed from in front of the second arm, while the same movement causes the tooth 68 to again project in 110 the path of the remaining arms and prevents them turning until the player desires to turn over the next leaf of music. The tooth 68 is of hinge construction, it being pivoted on a pin 69, and bends to the rear when pressure 115 is brought to bear upon it from the front. This allows the arms to be readjusted for operation in the manner described of the escapement 11. The tooth 68 is normally held extended by the spring 70, which is tensioned 120 when the said tooth is bent to the rear. Said escapement is operated by the same means as the escapement 11. The spring-retracted levers 93 and 93^a are fastened to the escape- 125 ment.

Another equivalent escapement, Fig. 14, consists of a plurality of tooth-carrying members 71, pivoted on an axle 72, and a successive depressing device 74. Each tooth-carrying member has pivotally secured to it one of the teeth 73. Said teeth normally project downward from their tooth-carrying members, but yield to the rear when pressure is brought to bear upon them from the front for the purpose given in the description of the teeth 16 in the above. The one end of the springs 75, one on each tooth, is tensioned when the teeth 73 are bent to the rear and cause them to resume their normal positions. A projection 76, one on each tooth, prevents their respective teeth from bending to the front. The other ends of the springs are coiled in circular recesses 77, one on each tooth-carrying member, and are fastened to a groove 78 on the axle 72. These other ends of the springs 75 normally hold the tooth-carrying members 71 in a slightly-upward position at approximately fifteen degrees from horizontal. The successive depressing device 74 consists of a shaft 79, having mounted thereon a plurality of projections 80, one of them for each tooth-carrying member. Said depressing device 74 revolves in the same way as the escapement 11 and is caused by the same means. These projections 80 successively come in contact with their respective tooth-carrying members and cause same to be depressed, so that the teeth 73 successively project in the path of the leaf-turning arms. The coiled ends of the springs 75 in the circular depressions 77 cause their respective tooth-carrying members to regain their normal positions when the respective projections 80 have revolved so far as to cease being in contact with said tooth-carrying members. A tooth-carrying member regaining its normal position in this manner removes its respective tooth from in front of the arm it held and the said arm is then released.

The equivalent escapement, Fig. 15, consists of a plurality of tooth-carrying members 81, each carrying a pivotally-mounted tooth 82. Said tooth-carrying members are pivotally mounted on an axle 83 and are normally held downward in approximately fifteen degrees from vertical by the upper part of the coiled springs 84, which are contained in the circular recesses 85 of the said tooth-carrying members. The upper ends of the springs 84 are fastened to the axle 83 in the groove 86. The other ends of the said springs are secured to the teeth 82 and normally keep them projecting downward. Said teeth are adapted to bend to the rear, for the same purpose as the teeth 16 of the escapement 11. Said tooth-carrying members 81 are successively deflected from their normal positions and cause the teeth 82 to successively project in the path of the arms by the deflecting device

87, constructed and operated the same as the depressing device 74 of the escapement, Fig. 14.

In the music-leaf turner, Fig. 19, the music-leaf-turning mechanism A is mounted upon the front face of a pivotally-mounted panel 88 in an opening on the front board of pianos and organs. The vise B and the finger-lever C^a are also mounted on the said panel 88. The finger-lever C^a is not provided with the recess 36, as is the finger-lever C. It is unnecessary here. The flexible tube E is connected to a metal tube 89. Said metal tube fits over the end of a metal tube 90, which is connected to the metal tube 25 of the music-leaf-turning mechanism A, and also serves as a point of pivot for the panel 88. In this way the bellows D always has communication with the metal tube 25 of the music-leaf-turning mechanism A regardless of the position of the panel 88 in relation to the front board. The panel 88 is shown partly reversed. The tube 90 and the rod 30 are placed inside the thickness of the panel 88, so that its rear face has no projecting parts. When the music-leaf turner is not in use, the panel 88 is reversed, so that its empty rear face comes to the front. The latch 91 serves to hold the panel 88 parallel to the front board.

The music-leaf turner, with the exception of the bellows D, is shown mounted on a stationary music-leaf rack of an organ, Fig. 20. The music-leaf-turning mechanism A together with vise B and the finger-lever C^a are mounted on the front face of the said rack. Said parts operate as already above described.

The music-leaf turner, with the exception of the bellows D, is shown, Fig. 21, mounted in a sunken panel on the front board of a piano or organ. The music-leaf-turning mechanism A together with the vise B and the finger-lever C^a are mounted on the front face of said panel. Two sliding doors 92 and 92^a cover these parts when not in use.

What we claim, and desire to secure by Letters Patent of the United States, is—

1. In a music-leaf turner, in combination, a series of independently-swinging arms having means to engage the leaves, and an escapement mechanism comprising a shaft having a series of hinged teeth arranged to engage said arms respectively and to release the same by rotation of the shaft.

2. In a music-leaf turner, in combination, a series of independently-swinging arms having means to engage the leaves, and an escapement mechanism comprising a shaft having thereon a series of hinged teeth projecting from the shaft in different directions and engageable with the arms, and means to turn the shaft intermittently, to release the arms successively.

3. In a music-leaf turner, in combination, a

series of swinging leaf-carrying arms, and an escapement mechanism comprising a shaft having thereon a ratchet and a series of teeth engaging the arms respectively, and a manually-operated pawl engageable with the ratchet to turn the shaft.

4. In a music-leaf turner, in combination, a series of swinging leaf-carrying arms, an escapement mechanism having a shaft provided with teeth engaging the arms, and pneumatically-actuated means to turn the shaft intermittently, to release the arms successively.

5. The combination with a music-board having a reversible section, of a music-leaf turner on the board, and a music-holding clamp on said reversible section, arranged to

hold music-sheets at the fold when they are engaged by the turner.

6. The combination with a music-board having a slot therein, of a music-leaf turner having a series of arms which may be advanced or retracted through the slot, and a flap arranged to cover the slot when the arms are retracted.

In testimony whereof we have signed our names to this specification, in the presence of two subscribing witnesses, this 21st day of March, 1905.
